US0D1000196S

(12) **United States Design Patent** (10) Patent No.: **US D1,000,196 S**
Smith et al. (45) Date of Patent: ** Oct. 3, 2023

(54) **CONTAINER LID**

(71) Applicant: **ALL PLASTIC, INC.**, Rancho Cordova, CA (US)

(72) Inventors: **William Thomas Smith**, Fair Oaks, CA (US); **Cheryl Ann Smith**, Fair Oaks, CA (US)

(73) Assignee: **ALL PLASTIC, INC.**, Rancho Cordova, CA (US)

(**) Term: **15 Years**

(21) Appl. No.: **29/870,190**

(22) Filed: **Jan. 18, 2023**

Related U.S. Application Data

(60) Division of application No. 29/725,666, filed on Feb. 26, 2020, now Pat. No. Des. 979,322, which is a continuation of application No. 16/502,168, filed on Jul. 3, 2019, now Pat. No. 11,001,413, which is a continuation of application No. 15/464,823, filed on Mar. 21, 2017, now Pat. No. 10,384,834, which is a continuation-in-part of application No. 14/701,961, filed on May 1, 2015, now Pat. No. 9,630,747.

CLAIM

The ornamental Design for a container lid, as shown and described.

DESCRIPTION

FIG. 1 is a perspective environment view taken from the top, front, right of a container lid;

FIG. 2 is an exploded perspective environment view taken from the top, front, right of the container lid of FIG. 1;

FIG. 3 is another exploded perspective environment view taken from the top, rear, right of the container lid of FIG. 1;

FIG. 4 is a side view of the container lid of FIG. 1;

FIG. 5 is a cross-sectional view of the container lid of FIG. 4, taken along line 5-5 in FIG. 4; and,

FIG. 6 is a perspective view taken from the top, front, right of the container lid of FIG. 1.

The portions shown in dashed broken lines depict environmental structure and form no part of the claimed design.
